SPLIT LEVEL BOWL

Norman S. Duncan, Barrington, N. J.

Application July 22, 1955, Serial No. 37,088

Term of patent 7 years

(Cl. D44—15)

I claim:

The ornamental design for a split level bowl, as shown.
